DESIGN FOR A PORTABLE SEARCH LAMP

George E. Gravenstine, Dayton, Ohio, assignor to
The S. H. Thomson Manufacturing Company,
Dayton, Ohio, a corporation of Ohio

Application July 29, 1940, Serial No. 93,999

Term of patent 14 years

To all whom it may concern:

Be it known that I, George E. Gravenstine, a citizen of the United States of America, residing at Dayton, in the county of Montgomery, State of Ohio, have invented a new, original, and ornamental Design for a Portable Search Lamp, of which the following is a specification, reference being had to the accompanying drawing, forming a part thereof.

In the drawing

Fig. 1 is a perspective view of a portable search lamp showing my new design;

Fig. 2 is a side view of the lamp; and

Fig. 3 is a plan view of the lamp.

The dominant features of my design reside in the portions shown in full lines.

I claim:

The ornamental design for a portable search lamp, substantially as shown and described.

GEORGE E. GRAVENSTINE.
